UNITED STATES PATENT OFFICE.

LLOYD W. WARD, OF BUCKHANNON, WEST VIRGINIA, ASSIGNOR OF ONE-HALF TO WILLIAM S. O'BRIEN, OF BUCKHANNON, WEST VIRGINIA.

THILL-COUPING.

No. 843,724.

Specification of Letters Patent.

Patented Feb. 12, 1907.

Application filed June 4, 1906. Serial No. 320,106.

To all whom it may concern:

Be it known that I, LLOYD W. WARD, a citizen of the United States, residing at Buckhannon, in the county of Upshur and State 5 of West Virginia, have invented a new and useful Thill-Coupling, of which the following is a specification.

This invention relates to thill-couplings.

The object of the invention is to provide a 10 simple and improved form of thill-coupling by means of which the shafts of the vehicle can be attached to or detached from the body portion when in raised position and firmly locked thereon against accidental detachment when in horizontal position.

A further object of the invention is to provide a coupling of the character set forth which can be lubricated, if desired, to permit an easy up-and-down movement of the 20 shafts without creaking and which is provided with improved means for protecting the lubricated parts, so as to prevent the entrance of grit, dirt, rain, or the like.

A still further object of the invention is to 25 provide improved means for holding the parts of the coupling yieldingly together and for preventing them from rattling in the event that they should become worn; furthermore, to hold the shafts in vertical 30 raised position when the vehicle is not in use.

With the foregoing and other objects in view, which will appear as the description proceeds, the invention resides in the combination and arrangement of parts and in the 35 details of construction hereinafter described and claimed, it being understood that changes in the precise embodiment of invention herein disclosed may be made within the scope of the claims without departing 40 from the spirit of the invention or sacrificing any of its advantages.

In the accompanying drawings, forming a part of this specification, Figure 1 is a perspective view of a thill-coupling constructed 45 in accordance with the invention, the axle member and the shaft member being shown in separated position. Fig. 2 is a vertical section through the two members. Fig. 3 is a horizontal section, partly in elevation. 50 Fig. 4 is a perspective view, partly broken away, of a slightly-modified construction.

Like reference-numerals indicate corresponding parts in the different figures of the drawings.

The improved thill-coupling of this invention, broadly speaking, comprises two members—an axle member (designated generally by A) and a shaft member, (designated by B.)

The axle member A consists, preferably, of a U-shaped axle-clamp 1, which is formed with threaded parallel ends 2 and 3, the end 2 having a lug or offset 4 and the end 3 having laterally-extending shoulders 5. The axle-clamp 1 is fitted around the axle 6 in the usual manner and is provided with a cross-piece 7, having perforated ends to receive the threaded parallel ends 2 and 3 of the clamp, said cross-piece resting against the lower surface of the axle as well as against the offset 4 and shoulders 5. The cross-piece 7 preferably is secured in position by means of nuts 8 engaging the threaded ends 2 and 3.

Suitably secured to or formed integral with the laterally-extending shoulders 5 of the clamp 1 is a forwardly-extending yoke 9, in which a core 10 is suspended by means of trunnions 11. The core 10 may be either circular in shape, as shown in Fig. 1, or segmental in shape, as shown in Fig. 4, said core in both instances being preferably formed with rounded edges. The yoke 9 preferably is thickened on its upper surface, as indicated at 12, adjacent to the trunnions 11, so as to provide a strong bearing for said trunnions. The lower portion of said yoke 85 preferably is cut upward on an incline from its rear to its forward end, as shown clearly in the drawings, the outer portions of said yoke being preferably rounded, so as to prevent the formation of sharp corners.

The shaft member B preferably comprises a shaft-iron 14, which is secured to the shaft in any suitable manner, such as by means of bolts or nails. At its rear end the shaft-iron 95 preferably is provided with an enlarged head, (designated generally by 15.) The head 15, which preferably is formed in one piece, is shaped so as to produce an approximately semicircular guard-flange 16, forming an inner socket, which depends from the head and fits snugly around the forward end 100 of the yoke 9, so as to perform the threefold function of preventing the shaft from being displaced rearwardly, concealing the yoke 9, 105 and protecting it from dirt and rain. The head 15 in rear of the guard-flange 16 is formed with a downwardly and rearwardly

curved tongue 17, which preferably is scoop-shaped and is bent on a curve approximately concentric with the semicircular guard-flange 16. It will thus be seen that with this arrangement of parts two substantially concentric sockets are formed within the end of the shaft member, and when the shafts are raised into vertical position the scoop-shaped tongue is adapted to be fitted down between the forward end of the yoke 9 and the core 10, so that when the shafts are lowered into horizontal position the tongue 17 slides around the core 10 until its lower rear end lies underneath the core and said core rests within the outer socket, which is formed by the tongue 17, so as to prevent the shafts from being withdrawn accidentally in a horizontal direction from the axle member A. The head 15 in addition to the guard-flange 16 and scoop-shaped tongue 17 is also formed with a rearwardly-extending protecting-web 18, which when a circular core 10 is employed is preferably scoop-shaped, so as to fit down upon the core 10 when the shafts are in vertical position and to cover the upper end of said core when the shafts are in horizontal position. When, however, a segmental core, such as shown in Fig. 4, is employed, the protecting-web 18 may be flat or of any other shape suitable for covering the core 10 when the shafts are in horizontal position.

It will be understood that, if desired, lubricating-grease can be applied to the core 10 and yoke 9, as well as to the tongue 17, guard-flange 16, and under side of protecting-web 18, so that all these parts will coöperate readily together and will permit an easy up-and-down movement of the shafts in driving, it being understood that the scoop-shaped tongue 17 will hold the lubricant against the under portion of the core 10 and that the guard-flange 16 and protecting-web 18 will serve to prevent the entry of dirt and rain from the upper side of the coupling.

45 The improved means which I employ for holding the members A and B of the coupling yieldingly together, so as to prevent rattling thereof when they become worn, as well as to hold the shafts in vertical position when the vehicle is not in use, preferably comprises a flat spring 20, the rear end of which rests upon the cross-piece 7 and is formed with an open-ended slot 21 to fit around the rear end 2 of the axle-clamp 1 and a perforation 22 to receive the threaded end 3 of the clamp 1. At its forward end the spring 20 is bent upward, so as to provide a free resilient portion which bears against the rear edge of the protecting-web 18 of the head 15, the extreme upper end 60 of said spring 20 being bent slightly backward to form a lip 23, which causes the spring to flex backward when the shaft member B is inserted outwardly into the axle member A. As before explained, the function of the spring 20 is to press the shaft member B for-

ward with respect to the axle member A, so as to prevent undue rattling of said members in the event that they should become slightly worn. Furthermore, the shape of the rear edge of the web 18 is such that when the shafts are pushed upward into vertical position without withdrawing them from their engagement with the axle member B the spring 20 will serve to hold them in their vertical position, as will be apparent.

The coupling of this invention is strong, simple, durable, and inexpensive in construction, as well as thoroughly efficient in operation.

What is claimed is—

1. A thill-coupling comprising a yoke, a core, a scoop-shaped tongue adapted to fit between the yoke and core, a semicircular guard-flange concentric to the scoop-shaped tongue, and a protecting-web to cover the core.

2. A thill-coupling comprising an axle-clamp, a yoke connected with said axle-clamp, a core having trunnions engaging said yoke, a shaft-iron having a head, a scoop-shaped tongue connected with said head and adapted to fit between the yoke and core, a guard-flange connected with said head, and a protecting-web connected with said head.

3. A thill-coupling comprising an axle-clamp, a yoke connected with said axle-clamp, a core carried by said yoke, a shaft-iron having a head provided with a scoop-shaped tongue to engage the yoke, a protecting-web to cover the core, and a spring connected with said axle-clamp and bearing against said protecting-web for the purposes set forth.

4. A thill-coupling comprising an axle member and a shaft member, a yoke extending from one of said members and a core mounted therein, the other member engaging the core and straddling the yoke.

5. A thill-coupling comprising a shaft member and an axle member, one of said members having a yoke extending therefrom, a core therein, and trunnions extending from the core and within the yoke, the other member engaging the core and adapted to straddle the yoke.

6. A thill-coupling comprising an axle member and a shaft member, one of said members having a yoke extending therefrom and a core therein and spaced therefrom, and the other member being adapted to straddle the yoke and having substantially concentric sockets for receiving the core and yoke respectively.

7. A thill-coupling comprising an axle member and a shaft member, one of said members having a yoke extending therefrom and a core therein and spaced therefrom, and the other member being adapted to straddle the yoke and having substantially concentric sockets for receiving the

core and yoke respectively, and resilient means for exerting a constant pressure upon the socketed member to prevent rattling.

8. A thill-coupling comprising an axle member and a shaft member, one of said members having a yoke extending therefrom and a core therein and spaced therefrom, and the other member being adapted to straddle the yoke and having substantially concentric sockets for receiving the core and yoke respectively, a web projecting

from the socketed member, and resilient means for bearing upon the web to hold said socketed member in either of two positions.

In testimony that I claim the foregoing as my own I have hereto affixed my signature in the presence of two witnesses.

LLOYD W. WARD.
